COMBINATION SINK AND LAUNDRY TRAY

Filed June 7, 1928

INVENTOR

Raymond L. Barton

UNITED STATES PATENT OFFICE.

RAYMOND LEONARD BARTON, OF LOS ANGELES, CALIFORNIA.

DESIGN FOR A COMBINATION SINK AND LAUNDRY TRAY.

Application filed June 7, 1928. Serial No. 27,031. Term of patent 14 years.

To all whom it may concern:

Be it known that I, RAYMOND L. BARTON, a citizen of the United States, residing at Los Angeles, in the county of Los Angeles and State of California, have invented a new, original, and ornamental Design for a Combination Sink and Laundry Tray, of which the following is a specification, reference being had to the accompanying drawing, forming part thereof.

The figure is a perspective view of a combination sink and laundry tray, showing my new design.

I claim:

The ornamental design for a combination sink and laundry tray, substantially as shown.

RAYMOND LEONARD BARTON.
